UNITED STATES PATENT OFFICE.

ARTHUR S. REESE, OF WASHINGTON, PENNSYLVANIA, ASSIGNOR TO TYGART VALLEY
GLASS CO., OF WASHINGTON, PENNSYLVANIA, A CORPORATION OF WEST VIRGINIA.

DESIGN FOR A DECANTER.

Application filed May 10, 1927. Serial No. 21,920. Term of patent 3½ years.

To all whom it may concern:

Be it known that I, ARTHUR S. REESE, a citizen of the United States, residing at Washington, in the county of Washington, State of Pennsylvania, have invented a new, original, and ornamental Design for a Decanter, of which the following is a specification, reference being had to the accompanying drawing, forming a part thereof.

The figure is a perspective view of a decanter, showing my new design.

I claim:

The ornamental design for a decanter, as shown.

ARTHUR S. REESE.
